[57] CLAIM

The ornamental design for a revolving tie rack, as shown and described.

DESCRIPTION

FIG. 1 is a top, front and right side isometric view of a revolving tie rack, showing my new design, the ties for use therewith shown in broken lines being for illustrative purposes only and forming no part of the claimed design; FIG. 2 is a top plan view thereof;

FIG. 3 is a front elevational view thereof;

FIG. 4 is a left side elevational view thereof, the right side elevational view not being shown separately, since it is a mirror image of the left side elevational view thereof;

FIG. 5 is a rear elevational view thereof; and,

FIG. 6 is a bottom plan view thereof.
